LOCOMOTIVE BOILER

Filed Aug. 17, 1929

Inventor:
Bert C. Larson
By Arthur Spurk
H. Horner.

UNITED STATES PATENT OFFICE

BERT E. LARSON, OF PARK RIDGE, ILLINOIS, ASSIGNOR TO LOCOMOTIVE FIREBOX COMPANY, OF CHICAGO, ILLINOIS, A CORPORATION OF DELAWARE

LOCOMOTIVE BOILER

Application filed August 17, 1929. Serial No. 386,659.

This invention relates to improvements in locomotive boilers and it consists of the matters hereinafter described and more particularly pointed out in the appended claims.

5 The primary object of the invention is to provide in a thermic siphon equipped boiler of this kind, a simple and an improved connection between the inlet neck of the siphon and associated part of the boiler where-
 10 by said neck may shift to accommodate itself to the movement of the siphon due to changes in temperature conditions.

The above mentioned object of the invention as well as others, together with the many 15 advantages thereof will more fully appear as I proceed with my specification.

In the drawings:—

Fig. 1 is a longitudinal vertical sectional view through the front throat portions of a 20 locomotive boiler and adjacent parts embodying the preferred form of my invention.

Fig. 2 is a transverse vertical sectional view through the same as taken on the line 2 of Fig. 1.

25 Referring now in detail to that embodiment of the invention illustrated in the accompanying drawings, 1 indicates as a whole the bottom portion of the shell of a locomotive boiler, 2 indicates the outside front 30 throat sheet associated therewith and 3 indicates the inside front throat sheet defining a part of the firebox 4. The bottom portions of the throat sheets 2 and 3 are connected together by a part of the mud ring 5 to provide 35 the front throat or water leg 6. The firebox includes a combustion chamber 7 the bottom wall 8 of which joins at one end with the throat sheet 3 and is secured at its other end to a flue sheet 9. To said flue sheet are 40 connected, the usual flues 10 through which products of combustion from the chamber 7 pass on the way to the usual smoke box at the front end of the boiler in the manner well known. From the construction just de-
 45 scribed which represents general practice in locomotive boilers of this kind, it is apparent that the front throat or leg is in communication with the boiler water space of the boiler beneath the combustion chamber.

50 Where additional elements are employed

in the combustion chamber 7 for increasing the water steaming and circulating efficiency of the boiler as a whole, such as for instance the well known Nicholson thermic siphon, difficulty has arisen in providing a suitable 55 connection for the neck end thereof with the boiler. In this respect it is pointed out that owing to the fact that such siphons are rigidly fixed at one end in the crown sheet and are subjected to varying temperatures, 60 they take on a movement relative to the parts of the boiler and firebox in which their opposite ends are connected. To accommodate such movement I have provided a structure associated with the tubular inlet end of the 65 siphon whereby such movement is permitted in the plane of and parallel with the axis of said neck and this without leakage.

11 indicates the substantially, perpendicularly disposed tubular inlet neck of a siphon 70 which extends down through but out of engagement with a sleeve 12, secured at its ends in the shell 1 and bottom wall 8 of the combustion chamber. The inlet neck 11 extends into a plane below that of the bottom end of the sleeve 12 and there has secured to it a collar 11^a of metal unaffected by immersion in water. Secured to the shell 1 so as to enclose the bottom end of said neck is a longitudinally extending cup shaped well member 13. Said member includes a bottom wall 14 and side and end walls 15 and 16 respectively, which are flanged at their top ends to fit and be tightly secured to the outer cylindrical surface of the shell 1. The shell in this instance is provided with openings 17 whereby communication is established between the boiler water space of the shell and the front end of the well.

Secured in any suitable manner to the bottom surface of the boiler shell 1, within the well member 13 and coaxially with respect to the sleeve 12, is a plate 18 which includes a depending annular flange 19 and an inwardly extending radial flange or shoulder 20 defining a recess 21 in said plate. In the bottom wall 14 of the well member 13, coaxially of the inlet neck end is an opening 22 normally closed by cover plate 23 fixed to said bottom wall preferably as by the rivets as shown. 100

A gasket 24 is provided between said bottom wall 14 and said cover plate to provide a tight joint therebetween. In said cover is also provided a washout plug 25.

5 In the recess 21 of the annular plate 18 is located a packing comprising coacting compressible packing rings 26 each surrounded by a contractile device 27 in the form of a helically coiled spring. 28 indicates a helical 70 expansion spring which engages at one end against the bottommost packing ring 26 and engages at its other end against the cover plate 23, the latter having legs 29 disposed inside the spring 28 to secure it against undue lateral movement.

10 As is apparent from the drawings, the spring 28 acts to hold the packing as provided by the rings 26, snugly up against the annular shoulder 20 and the springs 27 acts to contract said rings 26 about the collar 11^a in a manner providing a tight joint therebetween but one which will permit of a slip movement 80 of said collar without leakage.

15 Thus as the neck 11 moves longitudinally 25 under the action produced by temperature changes, the collar 11^a slides through the packing and as the packing rings have an inwardly contracting action upon said sleeve because of the springs 27 and are urged into 30 a tight engagement against the shoulder 20, it is, apparent that water cannot leak upwardly about the sleeve and through the packing.

20 Water from the boiler shell enters the well 35 member 13 and then passes into and up through the neck 11 which having its major portion disposed in the combustion chamber is subjected to the products of combustion therein. The steam evolved therein together 40 with the hot water will rise upwardly due to difference in weight between the water in said inlet neck and said boiler shell so that a siphonic action is induced, causing an upflow of water in said neck where it passes 45 to the body of the associated siphon in the manner well known.

25 The construction mentioned provides a slip connection for the inlet neck which consists of but a few parts disposed in a manner convenient for cleanout and inspection purposes.

30 While in describing my invention I have referred in detail to the form, arrangement and construction of the various parts thereof the same is to be considered merely as illustrative so that I do not wish to be limited thereto except as may be specifically set forth in the appended claims.

I claim as my invention:

35 1. A locomotive boiler embodying therein, a boiler shell sheet forming a part of the water space of the boiler, a member secured to said sheet and coacting therewith to form a well, a water circulating element having a tubular end extending through said sheet 65 into said well, a collar fixed on said tubular

end, means carried by said sheet and providing an annular shoulder in said well and radially spaced from said tubular end, a packing means surrounding said collar with a normal contracting action thereon and engaged against said shoulder and means disposed between said packing and said member for urging the packing against said shoulder.

2. A locomotive boiler embodying therein, 75 a boiler shell sheet forming a part of the water space of said boiler, means fixed to said sheet and providing a well below the same in communication with said water space, a water circulating element having a tubular end 80 extending through said sheet and into said well providing means, a collar fixed on said tubular end, means carried by said sheet in said well and providing an annular shoulder radially spaced from said tubular end, a packing means surrounding said collar with a normal contracting action thereon, and engaged against said shoulder and means disposed between said packing and said well 85 providing means for urging the packing 90 against said shoulder.

3. A locomotive boiler embodying therein a boiler shell sheet forming part of the water space of the boiler, means fixed to said shell sheet and providing a well below the 95 same in communication with said boiler water space, a water circulating member having a tubular end extending through said shell sheet and into said well, a collar fixed on said tubular end, an annular plate fixed to said 100 sheet within the well and providing an annular shoulder spaced radially from said collar, a packing engaged against said shoulder and normally surrounding said collar with a contracting action thereon, and spring means 105 disposed between said packing and well providing means and normally urging the packing against said shoulder.

4. A locomotive boiler embodying therein 110 a shell, a combustion chamber sheet spaced therefrom, a sleeve connecting said shell and sheet respectively, a member fixed to said shell and providing a well below the same, a member having a tubular end extending through said sleeve into said well, a collar fixed on said tube end, an annular plate fixed to said shell and providing an annular shoulder radially spaced from said collar, a packing engaged against said shoulder and surrounding said collar with a normal contracting action thereon, and a spring means disposed between said packing and well providing member and normally urging the packing against said shoulder.

5. A locomotive boiler embodying therein, 115 a shell, a combustion chamber sheet spaced therefrom, a sleeve connecting said shell and sheet respectively, a member fixed to said shell and providing a well below the same, a member having a tubular end extending 120

130

through said sleeve into said well, a collar fixed on said tube end, an annular plate fixed to said shell and providing an annular shoulder radially spaced from said collar, a packing engaging against said shoulder and surrounding said collar with a normal contracting action thereon, a removable cover in said well providing member, and a spring means disposed between said packing and said cover and normally urging the packing against said shoulder.

In testimony whereof, I have hereunto set my hand, this 13th day of August, 1929.

BERT E. LARSON.
